AUTOMATIC LANDING ELEVATOR SYSTEM

Alvin O. Lund, Great Notch, N. J., assignor to
Westinghouse Electric Corporation, East Pittsburgh, Pa., a corporation of Pennsylvania

Application June 26, 1952, Serial No. 295,705

18 Claims. (Cl. 187—29)

1

This invention relates to apparatus for controlling the position of a movable body and it has particular relation to automatic landing elevator systems wherein an elevator car is landed accurately at a floor regardless of the load carried by the elevator car.

In automatic landing elevator systems it is the practice to initiate a stopping operation of a moving body such as an elevator car at a predetermined distance from a point at which the body is to stop. If the load represented by the body remains constant, accurate stopping operations may be obtained. However, if the load represented by the body is subject to variation, the body may undershoot or overshoot the point at which it should stop. One solution for this problem will be found in my copending application, Serial No. 206,407, filed January 17, 1951, now Patent No. 2,641,337.

Although aspects of the invention are suitable for various types of moving bodies, the invention is particularly suitable for elevator systems and will be described with reference to a moving body in the form of an elevator car.

In an elevator system both mechanical and electrical braking have been employed. The mechanical brake conventionally is spring-applied and is released in response to energization of an electrical motor which may be in the form of a solenoid operating on a magnetic armature. Dynamic braking is well understood in the art, and may be employed not only for direct-current motors but for alternating-current motors such as induction motors to which direct current, for example, may be supplied for braking purposes.

In accordance with the invention, the braking of an elevator car is varied in accordance with the loading of the car. Such variation may be introduced in the mechanical braking or in the electrical braking, but in a preferred embodiment of the invention, the variation is introduced in both mechanical and electrical braking efforts.

In a preferred embodiment of the invention, a load-responsive device measures the load carried by an elevator. In addition, a source of energy is scanned to provide a variable output. The scanning of the source may be effected by a stepping switch which is responsive to the difference between the quantity measured by the load-responsive device and the output obtained from the source of energy. Adjusting devices are then controlled by the stepping switch for the purpose of adjusting braking efforts of mechanical and electrical braking apparatus. If a stopping operation of the elevator car is initiated at a predetermined distance from a point or floor from

2

which it is to stop, the adjustment of the braking efforts enables the elevator car to stop accurately at the desired point regardless of the load carried by the car.

It is therefore an object of the invention to provide an improved system for controlling the position of a movable body.

It is another object of the invention to provide improved load-responsive braking apparatus for a moving body.

It is a further object of the invention to provide load-responsive mechanical and electrical braking for a movable body.

It is also an object of the invention to provide an elevator system wherein load-responsive mechanical and electrical braking are initiated a predetermined distance from a point at which an elevator car is to stop.

It is an additional object of the invention to provide a control device for a variable load which includes a stepping switch responsive to the magnitude of the load.

It is a still further object of the invention to provide an elevator system wherein the braking of an elevator car is controlled by the position of a stepping switch which is responsive to the load carried by the elevator.

Other objects of the invention will be apparent from the following description taken in conjunction with the accompanying drawings in which:

Figure 1 is a schematic view with circuits shown in straight line form of an elevator system embodying the invention.

Fig. 1A is a key representation of electromagnetic switches and relays employed in the system of Fig. 1. If Figs. 1 and 1A are placed in horizontal alignment it will be found that corresponding coils and contacts of the switches and relays are substantially in horizontal alignment.

Fig. 1B is a schematic view of a stepping switch employed in the system of Fig. 1.

Fig. 1C is a vector diagram illustrating certain voltage relationships in the system of Fig. 1, and

Fig. 2 is a view in elevation with parts schematically shown of an inductor relay employed in the system of Fig. 1.

The relays and switches employed in the elevator system of Fig. 1 may have break or back contacts which are closed when the relay or switch is deenergized and dropped out. Each of the relays and switches employed in the system of Fig. 1 may have front or make contacts which are closed when the relay or switch is energized and picked up.

Each set of contacts of a relay or switch is

designated by the reference character for the relay or switch followed by a numeral specific to the set of contacts. For example, the reference characters U_1 and U_3 designate the first and third sets of contacts of the up switch U .

In order to facilitate the presentation of the invention, certain of the relays and switches may be listed as follows:

U—up switch
M—running relay
D—down switch
S—stop-control relay
F—inductor relay
LU—up-stopping relay
LD—down-stopping relay
BR—brake relay
 $10T$ —first timing relay
 $11T$ —second timing relay
A—auxiliary relay
DB—dynamic braking relay
T—third timing relay

Referring to the drawings, Fig. 1 shows an elevator system wherein an elevator car 10 and a counterweight 11 respectively are connected to the ends of a cable or rope 12 which passes over sheave 13 . Although various control systems may be employed for the elevator car, it will be assumed that a control system of the car-switch type is employed. In this system, a car switch CS is mounted in the elevator car for operation by an elevator car attendant.

In addition, the elevator car has secured thereto an inductor relay which cooperates with inductor plates mounted in the hoistway of the elevator car. For example, when the elevator car is at the second floor, the inductor relay F is located between a down inductor plate $2DP$ and an up inductor plate $2UP$. The down inductor plate $2DP$ controls the stopping of the elevator car during down travel of the car. A similar inductor plate is associated with each of the floors at which the elevator is to stop during down travel thereof.

The inductor plate $2UP$ controls the stopping of the elevator car at the second floor during up travel of the elevator car. A similar inductor plate is located at each of the floors at which the elevator car is to stop during up travel thereof.

The inductor relay is shown on a somewhat larger scale in Fig. 2. It will be noted that the inductor relay has four sets of break contacts F_1 , F_2 , F_3 and F_4 . Opening of any of the sets of contacts requires preliminary energization of the coil of the inductor relay. In addition, the set of contacts must be adjacent one of the inductor plates. It will be noted that the contacts F_2 and F_4 cooperate with the down inductor plates whereas the contacts F_3 and F_1 cooperate with the up inductor plates. Inductor relays of this general type are well known in the art. A typical inductor relay will be found in the Williams et al. Patent 2,326,086, which issued August 3, 1943.

Returning to Fig. 1, it will be noted that the sheave 13 is connected through suitable gearing 15 to the shaft 16 of an electric motor 17 . The motor may be of any suitable type but in the preferred embodiment of the invention a three-phase squirrel cage induction motor is employed having phase windings $17A$, $17B$ and $17C$. The phase windings are star connected through resistors RA , RB and RC for slow speed operation. For high speed operation, the resistors are shunted by make contacts A_1 and A_2 of an auxiliary relay A .

When the elevator car is to be moved, the phase windings of the motor 17 are connected for energization from a source of three-phase electric energization represented by buses LA , LB and LC , through make contacts M_1 and M_2 of a running relay M . These buses preferably represent a source having substantially constant voltage, such as the conventional distribution networks. The direction of movement of the elevator car is determined by a reversing switch which includes the make contacts U_1 and U_2 of an up switch U and the make contacts D_1 and D_2 of a down switch D . When the contacts U_1 and U_2 are closed, the buses LB and LC are connected to the motor properly for up travel of the elevator car. However, if contacts D_1 and D_2 are closed, the motor is connected for down travel of the elevator car.

When the elevator car is to stop at a floor, electrical or dynamic braking is provided by passing direct current through the phase winding $17C$. Such current is obtained from a transformer 18 which has its primary winding connected across the buses LA and LC through make contacts DB_2 of a dynamic braking relay DB and through an adjustable resistor R_1 . As hereinafter pointed out, the resistor R_1 is adjusted in accordance with the loading of the motor 17 .

The secondary winding of the transformer 18 is connected to a full-wave rectifier 19 and make contacts DB_1 and DB_3 of the dynamic braking relay to the phase winding $17C$. Consequently, a direct current dependent on the magnitude of the loading of the motor 17 is passed through the phase winding $17C$.

The shaft 16 of the motor 17 has secured thereto a brake drum 20 , which has a brake shoe 21 applied thereto by means of a spring BS . The brake is released as a result of the energization of its brake coil B . Release of the brake is accompanied by opening of the break contacts BI .

The coil B of the brake is energized from a source of direct current represented by a positive bus $L4$ and a negative bus $L5$. When the elevator car is conditioned to run, a release circuit for the brake is completed as follows: $L4$, U_3 or D_3 , B , BI , BR_1 , M_3 , $L5$. As soon as the brake is released, the contacts BI open to introduce a resistor R_2 in series with the brake coil B . The introduction of the resistor R_2 reduces the current passing through the brake coil to a value just sufficient to maintain the brake released. This decreases the heating of the brake coil.

During a stopping operation of the elevator car, make contacts BR_1 of a brake relay open to introduce a resistor R_3 in series with the brake coil B . This reduces the current supplied to the brake coil and the magnetic flux of the brake coil starts to decay. The decay need not be sufficient to produce any application of the brake. If employed in this manner the partial decay expedites the subsequent application of the brake. If desired, however, the resistor R_3 may be permanently shunted.

The application of the brake shoe 21 to the brake drum 20 is delayed by an adjustable discharge resistor R_4 which is connected across the brake coil through a rectifier R_5 . The rectifier blocks the flow of current in the resistor R_4 from the buses $L4$ and $L5$. However, the rectifier R_5 is properly poled to permit flow of the current produced by the collapsing magnetic field of the brake coil B following the disconnection of the brake coil from the buses $L4$ and $L5$. As hereinafter pointed out, the resistor R_4 is ad-

justed in accordance with a function of the loading of the motor 17 for the purpose of varying the braking effort as a function of such loadings.

The car switch CS is shown not only in the elevator car 18, but in association with circuits which are controlled by the car switch. It will be noted that the car switch normally occupies a stopping position wherein it connects a contact CS2 to the bus L4. Such connection controls in part the energization of a stop control relay S. The circuit for the stop control relay is completed through either make contacts M4 of the running relay or make contacts 70T1 of a first timing relay.

The car switch CS may be moved by the car attendant to an up position wherein it connects a contact CS3 to the bus L4. In this position, the car switch completes the following circuit: L4, CS, CS3, U, LU1, 22, M, L5. This circuit includes a limiting switch 22 which is normally closed, but which is cam operated to open as the elevator car nears its upper limit of travel. When the up switch U is energized, it closes make contacts U4 to establish a holding circuit around the car switch.

The car attendant also may operate the car switch to a down position wherein the car switch connects a contact CS1 to the bus L4. In this position the following circuit is completed: L4, CS, CS1, D, LD1, 23, M, L5. This circuit includes a limit switch 23 which is normally closed but which is cam operated to open as the elevator car nears its lower limit of travel. When energized, the down switch D closes its make contacts D4 to establish a holding circuit around the car switch.

Make contacts S2 of the stop control relay control the energization of the inductor relay F.

The break contacts F1 and F2 of the inductor relay respectively control the energization of the up stopping relay LU and the down stopping relay LD.

The brake relay BR is connected across the buses L4 and L5 in series with the make contacts M5 of the running relay and the break contacts F3 and F4 of the inductor relay. Under certain conditions, the break contacts F3 and F4 are bypassed through break contacts S4 of the stop control relay.

When the elevator car is conditioned to run, the first timing relay 70T is energized through make contacts M6 of the running relay. The relay 70T has a time delay in drop out which is provided in any suitable manner. For example, in Fig. 1 a resistor R6 is connected across the coil of the relay for the purpose of delaying drop out thereof.

Break contacts M7 of the running relay control the energization of a second timing relay 11T. This relay also has a time delay in drop out which is provided in any suitable manner as by connection of a resistor R7 across the coil of the relay.

The auxiliary relay A may be energized from the buses L4 and L5 through break contacts 11T1 of the second timing relay 11T and make contacts M8 of the running relay. Under certain conditions, these contacts are shunted by make contacts T1 of a third timing relay.

The dynamic braking relay DB is energized from the buses L4 and L5 through make contacts A4 of the auxiliary relay and break contacts M9 of the running relay.

The third timing relay T is energized from the buses L4 and L5 through the make contacts A4 75

of the auxiliary relay and the make contacts M10 of the running relay. The third timing relay has a time delay in drop out which is provided in any suitable manner as by connection of a resistor R8 across the coil of the relay.

It will be recalled that the adjustable resistors R1 and R4 are adjusted in accordance with a function of the loading of the motor 17. This function is determined by apparatus which includes three transformers 25, 26 and 27. The transformer 25 has a primary winding connected across a resistor R9 which is inserted in the bus LA. Consequently, the secondary winding of the transformer has an output voltage E1 which represents the current supplied to the phase winding 17A from the bus LA.

The transformer 26 has a primary winding connected for energization by the phase voltage E which is applied to the phase winding 17A of the motor. (Conveniently, the voltage E may be applied to the phase winding 17A and one or more of the resistors RA, RB or RC as shown). The secondary winding of the transformer 26 has a resistor R10 connected thereacross. This resistor has an adjustable tap 23 for the purpose of providing an adjustable voltage E2 which is dependent upon the phase voltage E.

The transformer 27 has a primary winding which is connected through the make contacts A3 across the buses LB and LC. This transformer has a secondary winding which is connected across a resistor R11. The resistor R11 has an adjustable tap 23 associated therewith to provide an adjustable voltage E3 which is dependent on the phase voltage appearing across the buses LB and LC.

By inspection of Fig. 1, it will be observed that the three voltages E1, E2 and E3 are combined vectorially in series. The resultant is applied through a rectifier 30 across an output resistor R12. A capacitor 31 is connected across the output resistor R12 for the purpose of bypassing any alternating component of the energization of the resistor.

The nature of the output appearing across the resistor R12 may be understood from a consideration of the vector diagram illustrated in Fig. 1C. The phase voltage appearing across the phase winding 17A of the motor 17 is represented in Fig. 1C by a vector E which is substantially constant in magnitude. The output voltage E1 of the transformer 25 is represented in Fig. 1C by a vector E1 which lags the reference voltage E. It will be recalled that the voltage E1 varies in accordance with the phase current supplied to the phase winding 17A of the motor.

The voltage E1 may be divided into two vector components. One of these vector components EP is in phase with the reference voltage E and represents the real power component of current supplied to the motor. The vector component EQ lags the reference voltage E by 90° and represents the reactive power component of current supplied to the motor. This reactive power component is substantially constant in magnitude.

The voltage E3 derived from the transformer 27 leads the reference voltage E by 90° and is proportioned to compensate for the vector component EQ. Consequently, the resultant of the outputs of the transformers 25 and 27 is represented by the vector component EP and this component represents the real power supplied to the motor.

The voltage E2 is derived from the transformer

26. The voltage E_2 has a phase relative to the vector EP and a magnitude which may be adjusted to control the magnitude of the resultant output.

It is conventional practice in the elevator field to provide a counterweight 11 which balances the weight of the elevator car 10 plus 40% of the rated load capacity of the elevator car. For this reason, the elevator motor 17 requires maximum power when carrying a full load in the up direction. For an overhauling load, the motor 17 generates power and the voltage EP consequently swings substantially 180° in phase relative to the voltage E_2 .

In the preferred embodiment of the invention the voltage E_2 compensates for a regenerative value of the voltage EP . Thus, the phase and magnitude of the voltage E_2 are so adjusted that if the elevator car is moving down with a full load (i. e. an overhauling load) the resultant voltage appearing across the resistor R_{12} is substantially zero. With this adjustment, if the elevator car is moving up with a full load the voltages E_2 and EP are in phase and a maximum voltage appears across the resistor R_{12} .

The output appearing across the resistor R_{12} is employed for controlling the adjustment of the resistors R_1 and R_4 . In a preferred embodiment of the invention, the output appearing across the resistor R_{12} controls the position of a stepping switch which in turn controls the adjustment of the resistors R_1 and R_4 .

The stepping switch STP is of conventional construction and may be understood from a consideration of Fig. 1B. The stepping switch includes a shaft 35 having four double-ended wipers or contact arms $35A$, $35B$, $35C$ and $35D$ secured thereto. The wiper $35A$ is employed for adjusting the effective resistance value of the resistor R_1 . The wiper $35B$ is employed for adjusting the effective resistance value of the resistor R_4 . The wiper $35C$ during successive stepping thereof successively engages contacts arranged in a semicircular bank. Only one of these contacts $35E$ actually is employed for resetting purposes. The wiper $35D$ is employed for controlling the effective resistance value of a resistor R_{14} .

The shaft 35 also has secured thereto a ratchet wheel $35F$. This ratchet wheel is successively stepped in the direction of the arrow by reciprocation of a pawl $35G$. When the coil of the stepping switch STP is energized, an armature associated therewith lifts the pawl $35G$ and simultaneously opens the break contacts $STP1$. Opening of the contacts $STP1$ is employed for deenergizing the coil of the stepping switch and the pawl thereafter drops under the influence of gravity or preferably a spring (not shown) to advance the ratchet wheel for an angular distance equivalent to one step. Such operation of a stepping switch is well known in the art. The number of steps required to rotate one of the wiper ends across its associated resistor may be selected to suit the specific application. As an example, twenty steps have been found adequate for some elevator applications of the type herein discussed.

As shown in Fig. 1, the coil of the stepping switch STP is energized from a secondary winding of a transformer 36 under the control of an electrical discharge device 37 , the break contacts $STP1$ and the make contacts $LU2$ and $LD2$. The electrical discharge device 37 may be of any suitable type wherein the output current thereof

5 may be controlled in a suitable manner. In the specific embodiment of Fig. 1, the electrical discharge device takes the form of an electronic tube having a cathode $37A$, a first grid or control electrode $37B$, a second grid or control electrode $37C$ and an anode $37D$. When the tube is in conductive condition, an energizing circuit for the coil of the stepping switch may be traced from one terminal of the secondary winding of the transformer 36 through the contacts $LD2$, $LU2$, $STP1$, the coil of the stepping switch STP , the anode $37D$, the cathode $37A$ to the remaining terminal of the secondary winding. The primary winding of the transformer 36 is energized from a suitable source of alternating current which may, for example, operate at the conventional power frequency of 60 cycles per second. Although the tube may be of the high vacuum type, a thyratron tube such as one sold under the type designation "2050" is considered to be very satisfactory.

10 In order to improve the operation of the stepping switch a rectifier 38 may be connected across the coil of the switch or preferably across the contacts $STP1$ as shown. This rectifier permits current to flow therethrough in the direction of the arrow. If desired a capacitor $C1$ and a resistor R_{15} may be connected across the contacts $STP1$ to decrease arcing thereof. The rectifiers employed in Fig. 1 may be of any suitable type, but preferably are of the dry type such as those known as copper oxide or selenium rectifiers.

15 When the stepping switch is in reset condition, the break contacts $S1$ and $S3$ of the stop control relay usually are closed, and the wipers occupy the positions illustrated in dotted lines in Fig. 1. Under these circumstances, the first grid $37B$ is connected to the cathode $37A$ through a resistor R_{16} and the contacts $S1$. In addition, the second grid $37C$ is connected through the contact $35E$, the wiper $35C$ and the contacts $S3$ to a point on a voltage divider comprising the resistor R_{14} and a resistor R_{17} . This point is located between the two resistors.

20 By inspection of Fig. 1 it will be observed that the resistors R_{14} and R_{17} are connected in series across a source of direct current represented by a positive bus $L7$ and a negative bus $L6$. The positive bus also is connected to the cathode $37A$ of the discharge device. Consequently, when the stepping switch is in reset condition, the second grid $37C$ is maintained negative relative to the cathode $37A$ to prevent occurrence of a discharge between the cathode and anode of the discharge device. A filter capacitor 40 is connected between the first grid $37B$ and the cathode, and a filter capacitor 41 , is connected between the wiper $35D$ and the positive bus $L7$.

25 When the stepping switch is to step to a position corresponding to the loading of the motor 17 , the break contacts $S1$ and $S3$ open. Opening of the contacts $S3$ removes the negative bias applied to the second grid $37C$. The second grid $37C$ now is connected to the cathode only through a resistor R_{18} .

30 The voltage appearing between the first grid $37B$ and the cathode $37A$ now depends on the difference between the voltage derived from the voltage divider represented by the resistors R_{14} and R_{17} , and the voltage derived from the resistor R_{12} . The biasing circuit may be traced from the first grid $37B$ through the resistor R_{16} , a resistor R_{20} , the resistor R_{12} , the wiper $35D$, the resistor R_{14} , and the resistor R_{17} to the cath-

ode 37A. The voltages are so related that the voltage across the resistor R12 tends to maintain the first grid positive with respect to the cathode whereas the voltage derived from the voltage divider tends to maintain the first grid negative with respect to the associated cathode.

At the start of an operation, the wipers and the stepping switches are in the positions represented in dotted lines in Fig. 1 and the output of the voltage divider represented by the resistors R14 and R17 is a minimum. Consequently, the voltage appearing across the resistor R12 in response to movement of a load in the elevator car places a positive bias on the first grid 37B and the discharge device 37 conducts to operate the stepping switch STP.

As the stepping switch operates, the wiper 35D moves in a clockwise direction as viewed in Fig. 1 to increase the grid voltage derived from the voltage divider represented by the resistors R14 and R17. The stepping of the stepping switch continues until the grid voltage derived from the voltage divider substantially balances the voltage appearing across the resistor R12. The position of the stepping switch then corresponds to the loading of the motor 17 and the resistors R4 and R1 are properly adjusted for a stopping operation of the elevator car. It will be assumed that such position of the stepping switch is represented in Fig. 1 by the full line positions of the various wipers.

When the stepping switch is to be reset, the break contacts S1 and S3 of the stop control relay close. Closure of the contacts S1 connects the first grid 37B to the cathode 37A through the resistor R16. Closure of the contacts S3 has no immediate effect on the system for the reason that the wiper 35C now is displaced from the contact 35E.

Because of the connection of the first grid 37B to the cathode, the discharge device 37 again becomes conductive and the stepping switch starts to step towards a resetting position. Such stepping continues until the wipers reach their dotted line positions whereupon the wiper 35C engages the contact 35E to place a negative bias on the second grid 37C. The negative bias terminates the discharge in the discharge device 37 and the stepping switch thereafter remains in its reset condition.

A complete operation of the elevator system now will be set forth.

Initially, it will be assumed that the elevator car 10 is located at the lower terminal floor and that the stepping switch is in its reset condition represented by the dotted line positions of the wiper arms in Fig. 1. Under the assumed conditions, break contacts F1 and F2 of the inductor relay are closed and the up stopping relay LU and the down stopping relay LD are energized and picked up.

The car attendant now operates his car switch CS to engage the contact CS3 and complete the following circuit: L4, CS, CS3, U, LU1, 22, M, L5. As a result of its energization, the up switch U closes its make contacts U1 and U2 to prepare the motor 17 for energization in proper direction for up travel. Make contacts U3 close to prepare the brake coil B for energization. Make contacts U4 close to establish a holding circuit around the car switch CS.

At the same time energization of the running relay M results in closure of the make contacts M1 and M2 to energize the motor 17. Closure of make contacts M4 has no immediate effect on the operation of the system. Closure of make

contacts M5 completes through the closed break contacts F3 and F4 an energizing circuit for the brake relay BR. This relay closes its make contacts BR1 to shunt the resistor R3. Inasmuch as the make contacts M3 also close, the following release circuit for the brake is completed: L4, U3, B, B1, BR1, M3, L5. The brake now is released and the motor 17 is energized to move the elevator car in the up direction. The release of the brake also is accompanied by the opening of the contacts B1 to introduce the resistor R2 in the energizing circuit for the brake coil. This reduces the current flowing through the brake coil to a value merely sufficient to maintain the brake in released condition.

Returning to the effect of the energization and pick up of the running relay, it should be noted that the pick up of the relay also closes the make contacts M6 to energize the first timing relay 70T. This relay closes its make contacts 70T1 without immediately affecting the operation of the system.

Opening of the break contacts M7 deenergizes the second timing relay 11T and this relay now starts to time out. Contacts M8 and M10 close and break contacts M9 open without immediately affecting the operation of the system.

Upon expiration of the time required for the relay 11T to drop out, this relay closes its break contacts 11T1 to complete through the closed contact M8 an energizing circuit for the auxiliary relay A.

As a result of its energization, the auxiliary relay A closes its make contacts A1 and A2 to shunt the resistors RA, RB and RC. Such shunting applies full energization to the motor 17 and conditions the motor for full speed operation of the elevator car in the up direction. The auxiliary relay also closes its make contacts A3 to energize the primary winding of the transformer 27. A voltage now appears across the resistors R12 which depends on the loading of the motor 17.

Closure of the make contacts A4 completes through the closed make contacts M10 an energizing circuit for the third timing relay T. The relay T thereupon closes its make contacts T1 to establish a holding circuit for the auxiliary relay A.

Let it be assumed that the elevator car attendant desires to stop the car at the third floor. A suitable distance in advance of the third floor he centers the car switch CS to engage the contacts CS2. Since the contacts M4 and 70T1 are closed, the stop control relay S is energized as a result of such centering of the car switch.

The stop control relay opens its break contacts S' to apply between the first grid 37B and the cathode 37A of the discharge device a voltage dependent on the difference between that appearing across the resistor R12 and the voltage derived from the voltage divider represented by the resistors R14 and R17. In addition, the break contacts S3 open to remove the negative bias from the second grid 37C.

The parameters of the system are assumed to be so selected that, with conventional counterweighing of the elevator car assembly and its load, when the elevator car carries a full load in the down direction zero voltage appears across the resistor R12. For an empty car traveling in the up direction an overhauling load having a smaller magnitude is applied to the elevator motor and voltage appears across the resistor R12. For increases in the load carried by the

11

up-traveling elevator car the voltage across the resistor R12 also increases.

It will be assumed that the up-traveling elevator car 10 is so loaded that a voltage appears across the resistor R12 requiring stepping of the stepping switch from the "zero" position represented by the dotted line positions of the wipers to the position represented by the full line positions of the wipers in Fig. 1. Under these conditions, a positive bias is applied to the first grid 37B and the discharge device 37 conducts to energize the coil of the stepping switch. The stepping switch now steps until the wiper 35D collects a sufficient voltage from the associated voltage divider to balance substantially the voltage appearing across the resistor R12. The stepping switch then remains in the position which is determined by the loading of the motor 17.

The pick up of the stop control relay is also accompanied by closure of the make contacts S2 to energize the inductor relay F. However, such energization alone is insufficient to pick up any of the contacts of the inductor relay. It will be recalled that in addition to energization of the coil of the inductor relay, each of the inductor relay contacts must be adjacent one of its associated inductor plates before such contacts can open. Opening of the break contacts S4 has no immediate effect on the system operation.

When the elevator car reaches a predetermined distance in advance of the third floor which may be of the order of 15 inches, the contacts F3 of the inductor relay reach the up inductor plate for the third floor and these contacts thereupon open to deenergize the brake relay BR.

Deenergization of the brake relay results in opening of the make contacts BR1 to introduce the resistor R3 in the energizing circuit for the brake coil B. The resulting decrease in energization of the brake coil B initiates a decay in the magnetic flux of the brake coil. It will be assumed that such decay does not result in application of the brake shoe 21 to the drum 20.

During continued motion of the elevator car, the contacts F1 of the inductor relay plate reach the inductor plate for the third floor and open to deenergize the up stopping relay LU. This may occur at a suitable distance from the third floor which may for example be of the order of 9 inches for a slow speed elevator car.

The up stopping relay LU opens the make contacts LU2 to prevent movement of the stepping switch during the stopping operation. In addition, contacts LU1 open to deenergize the up switch U and the running relay M. The running relay M opens its make contacts M1 and M2 to deenergize the elevator motor 17. In addition, the make contacts M3 open to deenergize the brake coil B.

The energy stored in the brake coil B now discharges through the resistor R4 and the rectifier R5. The resistor R4 has a resistance value as determined by the position of the wiper 35B which is properly coordinated for the purpose of stopping the elevator car 10 accurately at the third floor regardless of the magnitude of the load carried thereby. In the reset position of the wiper 35B the resistor R4 has a maximum effective value. However, the stepping of the stepping switch which followed the pick up of the stop control relay S decreased the effective resistance to a value determined by the car loading. Opening of the make contacts M4 and M5 has no immediate effect on the operation of the system.

12

The running relay also opens its make contacts M6 to deenergize the first timing relay 10T and this relay now starts to time out. Closure of break contacts M7 energizes the second timing relay 11T and the relay opens its break contacts 11T1 without immediately affecting the operation of the system. Opening of make contacts M8 also has no immediate effect on the operation of the system.

The closure of the break contacts M9 of the running relay energizes the dynamic braking relay DB through the closed contacts A4. The dynamic braking relay closes its make contacts DB1, DB2 and DB3 for the purpose of applying direct current to the phase winding 17C of the motor 17. The magnitude of the resultant dynamic braking is dependent on the position of the wiper 35A and this position is coordinated with the remainder of the system to stop the elevator car accurately at the third floor regardless of the loading thereof. In the reset position of the wiper 35A the resistor R4 is ineffective for limiting the energization of the primary winding of the transformer 18. However, the stepping of the stepping switch following the pick up of the stop control relay S progressively increases the effective resistance of the resistor R4 until it reaches a value representative of the car loading.

Returning to the running relay, this relay also opens its make contacts M10 to deenergize the third timing relay T and this relay now starts to time out.

At the expiration of its time delay, the third timing relay T drops out to open its make contacts T1. This results in deenergization and drop out of the auxiliary relay A. The relay A opens its make contacts A1, A2 and A3, but such opening does not immediately affect the operation of the system. Make contacts A4 open to deenergize the dynamic braking relay DB. This relay opens its make contacts DB1, DB2 and DB3 to terminate the supply of direct current to the motor 17.

Upon expiration of its time delay, the relay 10T drops out to open its contacts 10T1. This results in deenergization of the stop control relay S. The control relay closes its break contacts S1 to connect the first grid 37B of the discharge device to the cathode through the resistor R16. Contacts S3 close, but have no immediate effect on the operation of the system. Closure of contacts S4 has no immediate effect on the operation of the system.

Drop out of the stop control relay also results in opening of the make contacts S2 to deenergize the inductor relay F. This relay thereupon recloses its break contacts F1 and F3. Closure of the contacts F3 has no immediate effect on the operation of the system. Closure of the contacts F1 results in energization of the up stopping relay LU.

The up stopping relay closes its make contacts LU1 without immediately affecting the operation of the system. However closure of make contacts LU2 completes an energizing circuit for the stepping relay. It will be recalled that at the time of such closure the first grid 37B is connected to the cathode through the resistor R16 and the contacts S1. At the same time, the second grid 37C is connected to the cathode through the resistor R18. Under these conditions, the discharge device 37 conducts and the stepping switch steps until the wiper 35C engages the contact 35E. Such engagement places a negative

bias on the second grid 37C to terminate the stepping of the stepping switch. The stepping switch now remains in its reset condition.

Next it will be assumed that the elevator car is to be moved from the third to the second floor. To initiate such movement the car attendant operates his car switch CS to engage the contacts CS1 and complete the following circuit: 14, CS, CS1, D, LD1, 23, M, L5. The down switch D closes its make contacts D1 and D2 to prepare the motor 17 for energization with proper polarity for down travel of the motor. Make contacts D3 close to prepare the brake B for energization and release. Make contacts D4 close to establish a bypass around the car switch.

The running relay M operates in the manner previously described for up travel of the elevator car. However, since the closure of contacts D1 and D2 conditions the system for down travel, it follows that the elevator car now moves away from the third floor in the down direction.

As the elevator car nears the second floor, the elevator car attendant centers his car switch CS to complete an energizing circuit for the stop control relay S. This relay operates in the manner previously discussed to energize the inductor relay and to initiate a stepping operation of the stepping switch for the purpose of adjusting the stepping switch in accordance with the loading of the elevator motor.

When the elevator car reaches a distance such as 15 inches in advance of the third floor, the break contacts F4 of the inductor relay reach the down inductor plate for the second floor and open to deenergize the brake relay BR. Upon deenergization, the brake relay operates in the manner previously described to decrease the energization of the brake coil.

When the elevator car reaches a predetermined distance such as 9 inches in advance of the second floor, the contacts F2 of the inductor relay reach the down inductor plate for the second floor and open to deenergize the down stopping relay LD. The down stopping relay LD opens its make contacts LD1 to deenergize the down switch D and the running relay M. In addition, the make contacts LD2 open to prevent operation of the stepping switch during the stopping operation.

The running relay M upon deenergization operates in the same manner discussed for the stopping of the elevator car during up travel in order to stop the elevator car 10 accurately at the second floor. Upon the deenergization the down switch D returns its contacts to the conditions illustrated in Fig. 1.

With the assumed parameters it will be noted that when the elevator car travels down with a full load the stepping switch is positioned at the beginning of a stopping operation to apply maximum direct current to the motor, and to introduce the maximum effective value of the resistor R4 across the brake coil. Consequently, a substantial dynamic braking is available and the brake is rapidly applied. When the elevator car travels up with a full load the stepping switch is positioned at the beginning of a stopping operation to apply minimum direct current to the motor and to introduce a minimum effective value of the resistor R4 across the brake coil. The variations in direct current or dynamic braking and in the rate of application of the mechanical brake is proportioned to assure accurate landing of the elevator car at a floor regardless of the amount of load carried thereby.

Either the adjustment of the resistor R4 or the 75

dynamic braking may be omitted for some applications for which a single adjustment suffices. The dynamic braking is particularly desirable, and for applications in which the adjustment of the dynamic braking suffices the resistor R4 may be omitted or replaced by a fixed resistor providing a fixed discharge path for current produced by the decay of magnetic flux in the brake coil.

Although the invention has been described with reference to certain specific embodiments thereof, numerous modifications falling within the spirit and scope of the invention are possible.

I claim as my invention:

1. In a system for controlling a movable body, a structure, a body movable relative to said structure, motive means for moving the body relative to the structure, and control means for controlling movement of the body, said control means comprising first stopping means operable for mechanically braking said body as it approaches a predetermined point at which it is to stop, second stopping means operable for electrically braking said body as it approaches the predetermined point, and means responsive to energy to be absorbed during a stopping operation of the body for adjusting the braking effort exerted by each of said stopping means in accordance with the energy to be absorbed during a stopping operation of the body.

2. A system as claimed in claim 1 wherein the electric motor is an induction motor, and the second stopping means is effective for applying to the induction motor windings direct current having a magnitude which varies as a function of the energy to be absorbed during a stopping operation of the body.

3. In a system for controlling a movable body, a structure, a body movable relative to said structure, means for moving the body relative to the structure, and control means for controlling movement of the body, said control means comprising first stopping means operable for mechanically braking said body as it approaches a predetermined point at which it is to stop, second stopping means operable for electrically braking said body as it approaches the predetermined point, means for partially operating said first stopping means as it approaches the point, and means responsive to energy to be absorbed during a stopping operation of the body for operating each of the stopping means to adjust the braking effort exerted by each of the stopping means in accordance with the energy to be absorbed.

4. In a system for controlling a movable body, a structure, a body movable relative to the structure, motive means for moving the body relative to the structure, and control means for controlling movement of the body, said control means comprising first stopping means operable for mechanically braking said body as it approaches a predetermined point at which it is to stop, second stopping means operable for electrically braking said body as it approaches said predetermined point, means responsive to arrival of said body at a predetermined position in advance of said predetermined point for initiating operations of the first and second means, and means responsive to energy to be absorbed during a stopping operation of the body for adjusting the braking effort exerted by each of the stopping means in accordance with said energy to stop the body accurately at said predetermined point.

5. In a system for controlling a movable body,

a structure, a body representing a variable load movable relative to the structure, electromotive means for moving the body relative to the structure, and control means for controlling movement of the body, said control means comprising first stopping means operable for mechanically braking said body as it approaches a predetermined point at which it is to stop, second stopping means operable for supplying direct current to said body as it approaches said predetermined point, means responsive to arrival of said body at a predetermined position in advance of said predetermined point for initiating operations of the first and second means, and means responsive to the magnitude of said load for adjusting the braking effort exerted by the first stopping means and for varying the magnitude of the direct current to stop the body accurately at said predetermined point.

6. In an elevator system, a structure having a plurality of floors, an elevator car movable with respect to the structure to serve the floors, means including an electric motor for moving the elevator car relative to the floors, a mechanical brake operable for stopping the elevator car at any of said floors, auxiliary braking means operable for conditioning the electric motor to act as a dynamic brake, initiating means operable a predetermined distance from each of the floors for initiating a stopping operation of the elevator car as it approaches a floor at which it is to stop, and adjusting means responsive to the load on said elevator car for adjusting the braking effort exerted by the mechanical brake and for adjusting the braking effort exerted by the dynamic brake to stop the elevator car accurately at any of the floors for which a stopping operation is initiated.

7. An elevator system as claimed in claim 6 wherein the adjusting means is responsive to the power supplied to said motor for moving the elevator car.

8. An elevator system as claimed in claim 6 wherein the motor is an induction motor, and wherein auxiliary means comprises a source of direct current and connections for energizing the induction motor from said source to produce dynamic braking of the elevator car, said adjusting means being effective for adjusting the magnitude of the direct current supplied to said induction motor.

9. An elevator system as claimed in claim 6 wherein the adjusting means comprises a stepping switch, means for stepping the switch to a position corresponding to the elevator car load, and means responsive to the position of the stepping switch for adjusting said braking efforts.

10. In an elevator system, a structure having a plurality of floors, an elevator car movable with respect to the structure to serve the floors, means including an electric motor for moving the elevator car relative to the floors, a mechanical brake operable for stopping the elevator car at any of said floors, auxiliary braking means operable for conditioning the electric motor to act as a dynamic brake, initiating means operable when in effective condition a predetermined distance from each of the floors for initiating a stopping operation of the elevator car as it approaches a floor at which it is to stop, and adjusting means responsive when in effective condition to the load on said elevator car for adjusting the braking effort exerted by the mechanical brake and for adjusting the braking effort exerted by the dynamic brake to stop the elevator

car accurately at any of the floors for which a stopping operation is initiated, and effectuating means operable while the elevator car is in motion for placing said initiating means and the adjusting means in effective condition.

11. In a system for controlling a movable body, a structure, a body representing a variable load movable relative to the structure, means including an electric motor for moving the body relative to the structure, and control means for controlling movement of the body, said control means comprising means connecting the electric motor to provide dynamic braking for the body, adjusting means for adjusting the magnitude of the dynamic braking effort produced by the electric motor, and means responsive to the load represented by said body for operating the adjusting means to vary the dynamic braking effort in accordance with a predetermined pattern.

12. In a system for controlling a movable body, a structure, a body representing a variable load movable relative to the structure, means including an electric motor for moving the body relative to the structure, and control means for controlling movement of the body, said control means comprising braking means for braking said body, adjusting means for adjusting the braking effort of the braking means, a stepping switch having a movable operating member connected to operate said adjusting means and having stepping means operable when in effective condition for successively stepping the operating member to spaced positions, and means for energizing the stepping switch in accordance with the difference between a quantity representing said load and a quantity representing the displacement of the operating member from a predetermined position, whereby the stepping switch operates the adjusting means to produce a braking effort having a magnitude dependent on said load.

13. In a system for controlling a movable body, a structure, a body representing a variable load movable relative to the structure, means including an electric motor for moving the body relative to the structure, and control means for controlling movement of the body, said control means comprising braking means for braking said body, adjusting means for adjusting the braking effort of the braking means, a stepping switch having a movable operating member connected to operate said adjusting means and having stepping means operable when in effective condition for successively stepping the operating member to spaced positions, and means for energizing the stepping switch in accordance with the difference between a quantity representing said load and a quantity representing the displacement of the operating member from a predetermined position, whereby the stepping switch operates the adjusting means to produce a braking effort having a magnitude dependent on said load, operating means operable for placing said stepping means in effective condition, and initiating means responsive to operation of the operating means for initiating a braking operation of the braking means upon arrival of the body at a predetermined distance from a point at which the body is to be stopped, said adjusting means controlling the braking effort in accordance with said variable load to stop said body substantially at said point.

14. In a load-responsive device, translating means for actuating a variable load, an operating member, stepping means operable when in

effective condition for successively stepping the operating member to spaced positions, translating means for producing a first variable quantity dependent on the position of the operating member, load-responsive means for producing a second variable quantity dependent on the load on said translating means, and means for energizing the stepping switch in accordance with the difference between said first and second variable quantities, whereby the operating member seeks a position dependent on said load.

15. In a load-responsive device, translating means for actuating a variable load, an operating member, stepping means operable when in effective condition for successively stepping the operating member to spaced positions, translating means for producing a first variable quantity dependent on the position of the operating member, load-responsive means for producing a second variable quantity dependent on the load on said translating means, and means for energizing the stepping switch in accordance with the difference between said first and second variable quantities, whereby the operating member seeks a position dependent on said load, means operable for energizing the stepping means to move the operating member to a predetermined position, said last-named means placing said stepping means in effective condition.

16. In a system for controlling a movable body, a structure, a body movable relative to the structure, motive means for moving the body relative to the structure, and control means for controlling movement of the body, said control means comprising first stopping means operable for mechanically braking said body as it approaches a predetermined point at which it is to stop, second stopping means operable for electrically braking said body as it approaches said predetermined point, means responsive to arrival of said body at a predetermined position in advance of said predetermined point for initiating a partial operation of the first stopping means, and means responsive to arrival of the body at a second predetermined position between the first 45 predetermined position and the predetermined point for initiating joint operations of the first and second means, and means responsive to energy to be absorbed during a stopping operation

10

5 of the body for adjusting the braking effort exerted by each of the stopping means after the body reaches the second predetermined position in accordance with said energy to stop the body accurately in said predetermined point.

17. In a system for controlling a movable body, a structure, a body movable relative to the structure, motive means for moving the body relative to the structure, and control means for controlling movement of the body, said control means comprising stopping means operable for mechanically braking said body as it approaches a predetermined point at which it is to stop, means responsive to arrival of the body at a first predetermined position in advance of the predetermined point for partially operating the stopping means, and means responsive to arrival of the body at a second predetermined position located between the first predetermined position and the point for modifying the operation of the stopping means to increase the mechanical braking of the body to a value dependent on the load on said motive means.

25 18. In a system for controlling a movable body, a structure, a body movable relative to the structure, motive means for moving the body relative to the structure, and control means for controlling movement of the body, said control means comprising stopping means operable for mechanically braking said body as it approaches a predetermined point at which it is to stop, means responsive to arrival of the body at a first predetermined position in advance of the predetermined point for partially operating the stopping means, and means responsive to arrival of the body at a second predetermined position located between the first predetermined position and the point for modifying the operation of the stopping means to apply the mechanical braking of the body in accordance with a function of the load presented by the body to the motive means for stopping the body accurately at the point regardless of the load represented by the body.
